CONTROL MECHANISM

Victor F. Zahodiakin, Short Hills, N. J.

Application April 28, 1942, Serial No. 440,782

1 Claim. (Cl. 74—569)

This invention relates to improvements in Control mechanisms, and more particularly to an apparatus for controlling movement of a reciprocable member, such as machine gun triggers or the like, and is an improvement upon my prior application S. N. 382,127, filed March 7, 1941.

Objects

Among the principal objects which the present invention has in view are: to provide an improved control mechanism to function as an interceptor or stop for a reciprocable member; to provide such a stop in conjunction with a constant stroke-actuating prime mover without stopping the prime mover; to assure prompt and effective stopping of the reciprocation of the reciprocable member as desired; to definitely clear the reciprocable member from engagement with the prime mover when the reciprocable member is caused to stop reciprocating; to transfer clearance available for introducing the interceptor to function as the clearance for the prime mover; to entirely retract the interceptor from the path of movement of the reciprocable member while said member is reciprocating; to provide a brief dwell of interceptor with clearance between the stop and reciprocable member before transfer of the clearance to the relation of said member to the prime member; to precede the rotary and slide movement with a non-rotating slideable movement of the interceptor or stop; to provide simple and effective means for performing the sliding movement of the interceptor or stop; to employ a solenoid for effecting said movements; to translate the sliding moment of force of the solenoid into the desired sliding movement for the desired portion of stroke of the interceptor; to provide the interceptor with means whereby frictional engagement of the same will be greatly minimized; to provide means to prevent rotating the interceptor during operation; to keep the interceptor out of contact or frictional engagement with the body portion of the housing; to provide the interceptor with a roller centrally thereof and in engagement with a hard metal wall in the central bore of the housing; to obtain simple operation and construction; and to obtain other advantages and results as may be brought out in the following description.

Drawing

Figure 1 is a longitudinal vertical sectional view of a control mechanism embodying my invention, showing the interceptor in its unlocked position;

Figure 2 is a fragmentary horizontal sectional view showing the interceptor in top plan and in its unlocked relation as in Figure 1;

Figure 3 is a fragmentary horizontal sectional view similar to Figure 2 showing the interceptor in its entering position with respect to the reciprocable member;

Figure 4 is a sectional view similar to Figure 3, showing the interceptor in locked position; and

Figures 5 and 6 are sectional elevations of the reciprocable member showing its relationship to the prime mover and to the shouldered portions of the interceptor.

Description

There are often instances of reciprocation of a member wherein it is desired to interrupt or stop the stroke of reciprocation of such member. One such instance is in connection with the trigger or tripping mechanism of machine guns, and the present invention relates generically to the control mechanism applicable to any of the numerous apparatuses where a control of the stroke is desired. The present invention inheres in parts 15 associated with a reciprocable member by which the member is susceptible to being stopped and with which is associated mechanism for intercepting or stopping such stroke. Such embodiment is illustrated more particularly in Figures 1 to 6 in which reference numeral 15 designates in general a reciprocable member. The upper and lower end portions of said member are shown as aligned cylinders or rods 16 and 17 integrally connected by an intervening yoke portion 18. 20 The reciprocable member is carried in a suitable housing appropriately shaped to provide an upper bearing portion 19 for the upper rod portion 16 of the reciprocable member and a lower bearing portion 20 for the lower end portion 17 of said member. The member is permitted to have a reciprocation within said bearings, but is prevented from rotating by suitable means such as key-way 21 situated longitudinally of the lower rod portion 17 engaging a corresponding longitudinal spline 22 in the housing. The upper end of the reciprocable member 15 is shown connected by a wire or other connecting means 23, which is preferably flexible, to the particular device to which controlled reciprocation is to be applied. 25 A spring 24 is diagrammatically shown in connection with said connecting means 23 which tends to actuate the reciprocable member at all times towards the upper end of its stroke. The spring is to be understood as any tensioning means either incorporated in direct association

with the connection 23 or forming part of the apparatus to which the control mechanism of the present invention is applied.

In association with the reciprocal member 15 is a prime mover 25, here shown as a constantly rotating shaft transverse to the reciprocable member 15 and projecting through the yoke 18 thereof. Fast upon this shaft 25 is a cam 26 situated adjacent to said yoke 18 and rotatable in a plane parallel to said yoke. The said shaft and cam are constantly rotating under influence of suitable motivating means (not shown), such as an electric or other motor while the associated apparatus is in use. At the front of the yoke in a plane common to the plane of the cam is a roller 27 carried by a suitable bearing or stud 28 from the reciprocable member. At such time as said reciprocable member is free to respond to the tensioning of spring 24, the said roller 27 is drawn into peripheral contact with the periphery of cam 26. Consequently, as said cam rotates the reciprocable member will move upwardly under influence of the spring as the cam rotates to present its portion of diminishing diameter to the roller. As the cam proceeds to present its periphery of increasing diameter to the roller, the said member 15 is thereby depressed. The rotary action of said shaft and cam in conjunction with spring 24 will accordingly impart a reciprocating movement to reciprocable member 15 and as so far described, such reciprocation is for the full stroke which the cam is designed to impart, and with the roller in constant engagement with the cam.

In the upper rod portion 16 of the reciprocable member is provided a means for intercepting or stopping reciprocation of the said member 15 notwithstanding the continued and constant rotation of the prime mover. The means here shown contemplates the introduction of an interceptor or stop 29 as a limiting factor which is interposed in the path of movement of the reciprocable member. The specific limiting factor or interceptor here shown is the end of a bolt-like slidable non-rotatable member 29 transverse to the reciprocable member 15. While the bolt-like interceptor 29 is generally cylindrical, its end portion next the reciprocable member 15 has a plurality of upper and lower flattened areas which, as shown, are horizontal and at the top and bottom of the interceptor. The over-all dimension of each flattened area in a direction longitudinal of the interceptor is preferably substantially equal to the length of the stroke of the interceptor, and is shown as providing a forward stepped portion 30 somewhat deeper in a direction toward the axis of the interceptor than a rear step 30', the riser between steps having a slope rearwardly outward. The reciprocable member 15 is recessed or notched, as at 31, on its side toward the interceptor. The depth of the notch in a radial direction of the reciprocable member is also substantially equal to the length of stroke of the interceptor, and its dimension longitudinally of said reciprocable member is substantially equal to the full diameter of the interceptor. Accordingly, as can be best seen in Figures 1, 3 and 4, as the reciprocable member assumes a position with its notch 31 opposite to or in registration with its interceptor, the flattened areas 30 and 30' thereof affords a clearance 32 for easy entry of the interceptor end into the notch.

The interceptor is movably mounted in a lateral extension 33 of the housing, and is controlled

in its character of movement by a fixed stud 34 mounted in said housing. The stud is transverse to the interceptor, preferably extending upwardly with its upper end engaging against a cut-out 5 flattened surface portion 35 at the bottom of the stud lengthwise thereof. At the forward and rear ends of the flattened portion 35 the interceptor resumes full diametrical character thus providing projections at the ends of the flattened portion 10 which constitute stops 36, 36 determining the amplitude of reciprocation of the interceptor. Movement of the interceptor by virtue of the flattened surface portion 35 engaging the stud, will be strictly a straight longitudinal sliding motion, 15 without rotation permitted; whereby the flattened areas 30 and 30' at the forward end of said interceptor likewise move without turning, into the notch 31 of the reciprocable member. Thus I take advantage of the clearance afforded by flattening the forward end portions of the interceptor to assure easy insertion thereof into the reciprocable member.

It is a feature of the present invention to prevent undue wear in the interceptor 29 resultant from lateral thrust or pressure exerted thereagainst both by stud 34 and by reciprocable member 16. As shown, the portion of the bore of lateral extension 33 containing the interceptor is provided with a hardened sleeve or bushing 37, preferably of tempered steel. The central passage through this bushing is shown as substantially fitting the contained portion of the interceptor throughout the side areas of the said interceptor.

At opposite ends of the flattened surface portion 35 of the interceptor and rotatable in a common plane perpendicular with respect to said flattened portion, are two rollers 38, 38. These rollers are each within a vertical diametric slot 39 through the interceptor and protrude above and below the interceptor surface so as to substantially engage at opposite top and bottom ends of vertical diameters through said rollers against the inside surface of the bore of the bushing. Cutting of the slots 39 diametrically through the cylindrical interceptor chordally lessens the thickness of the interceptor from top to bottom thereof, and these lessened thicknesses at the slots extend oppositely from flattened surface portion 35 and cooperate therewith to depress the top and bottom surfaces of the interceptor for the full length thereof which travels within the bushing 37 so that all lateral thrust imparted to or by the interceptor in a direction parallel to the movement of the reciprocable member 16 will be transmitted between the interceptor and the bushing through the intervention of the rollers. Suitable pins 41 are inserted through the interceptor diametrically thereof and at the center of the rollers for rotatably mounting said rollers with respect to the interceptor. It is to be understood that said rollers 38, 38 have just sufficient clearance within the bushing to permit said rollers to rotate in contact with the bushing at one side of the interceptor only, but the direction of thrust determines at which side the rolling engagement occurs. The rollers are preferably of a hardened metal, such as tempered steel, and as they roll upon similar metal comprising the bushing 37, the wear between those parts will be infinitesimal over a long period of time.

The interceptor extends rearwardly a considerable distance in the housing extension 33 and is axially coincident with a solenoid coil 42 mounted therearound and supported from said housing extension. A tubular soft-iron or other

core 43 is shown carried upon the interceptor to move therewith. Influence of the solenoid coil, when energized, is to retract the interceptor. The outer end of the solenoid is provided with a head or cap 44 which retains a fixed position and forms a suitable support and guide for the protruding outer end of the interceptor. Between this cap and a suitable shoulder 45 on the interceptor is a compression spring 46 which functions to slide the interceptor inwardly toward the reciprocable member. Accordingly, when the solenoid coil is not electrically excited, the spring functions to slide the interceptor and introduce the forward end of said interceptor into the notch 31 the first time the notch registers with the interceptor. Prompt interception and stopping of the reciprocation of the reciprocable member is thus obtained upon opening of the electric circuit to the solenoid or upon discontinuance of the exciting current.

In event of failure of the electric circuit or if preferred to operate the retraction of the interceptor by manual means, suitable connection 47 may be made for that purpose. As here shown, said connection is in the form of a wire fastened by means of a lost-motion attachment to and extending from the rearmost end of the interceptor outward through a collar-like housing 48 on the outer end of cap 44. As shown, said wire or connection 47 passes through and is gripped by a contracting nut 49 screwed into a threaded bushing 50 which in turn is slidable within the end of the collar-like housing 48 and is slid inward by a compression spring 51.

I now wish to emphasize that while the prime mover is functioning to reciprocate the reciprocable member, that is to say, while the interceptor is retracted from engagement within the notch of the reciprocable member, the roller 27 on said reciprocable member is in continuous contact with the periphery of cam 26 of the prime mover. Operation of that cam reciprocates the reciprocable member so that in the regular cycle of operation, the lower wall of the notch 31 is situated periodically at a level below the plane of the flattened area 30 of the interceptor. This relationship occurs with each reciprocation and when the reciprocable member is at its lowermost position in each cycle of its movement. In view of the clearance 32 provided when the parts are as just described, there is no difficulty for the interceptor to engage within the notch practically immediately upon its release by the sole-

noid. The stepped construction of the flattened end of the interceptor assures introduction of the interceptor into the notch and obtains adequate holding depression of the reciprocable member as the more shallow step 30' rides into depressing and holding position.

I claim:

A control mechanism comprising a housing, a reciprocable member slidable in said housing and held therein against lateral displacement, said member having a notch therein at one side thereof, an interceptor in said housing transverse to said reciprocable member and longitudinally slidable in said housing toward and from said reciprocable member within the range of reciprocation of said notch, said interceptor having its top and bottom margins next one end of the interceptor toward the notch provided with successive flat steps transverse to the reciprocable member and providing clearance for entrance into the notch and flat surface engagement therewith, the step nearest the end of the interceptor providing greater entrance clearance into said notch than the next step, and the last step entering the notch with full stroke of the interceptor being at a level beyond the normal stroke of the engaged wall of the notch thereby positioning said reciprocable member beyond its normal stroke and stopping reciprocable actuation thereof, said end margins having sloping risers between steps for obtaining transitional engagement of successive steps with the notch wall, a hardened bushing in said housing girdling said interceptor and receiving the lateral thrust from the interceptor imparted thereto by the reciprocable member as the interceptor is positioned in said notch and the steps engage the wall thereof, rollers mounted in said interceptor spaced apart longitudinally of the interceptor and protruding from the same sides of the interceptor which have said steps, said rollers riding in contact with said bushing, said interceptor having a flattened area for a part of its length between said rollers, and a flat headed stud in said housing perpendicular to said flattened area of the interceptor and having the flat part of said head in slidable engagement with said flattened area of the interceptor whereby the interceptor is prevented from rotating and thrust imparted by said stud is counteracted by rollers at opposite sides thereof.

VICTOR F. ZAHODIAKIN.
